(57) **CLAIM**

The ornamental design for a security monitoring device, as shown and described.

DESCRIPTION

FIG. 1 is an exploded perspective view of a new design for a security monitoring device;

FIG. 2 is an exploded top view for the security monitoring device;

FIG. 3 is an exploded bottom view for the security monitoring device;

FIG. 4 is a right side view for the security monitoring device, where the solid white line designates the border between the two pieces when joined together;

FIG. 5 is a left side view for the security monitoring device;

FIG. 6 is an exploded top view for the security monitoring device; and,

FIG. 7 is an exploded bottom view for the security monitoring device.

The surfaces of the security monitoring device as shown in FIGS. 1-7 are illustrated at least partially in solid black to show color contrast in accordance with 37 CFR 1.152.
